UNITED STATES PATENT OFFICE.

HOWARD TERHUNE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

DROP-HAMMER.

1,246,183.

Specification of Letters Patent. Patented Nov. 13, 1917.

Application filed June 26, 1916. Serial No. 105,869.

To all whom it may concern:

Be it known that I, HOWARD TERHUNE, a citizen of the United States, and a resident of Chambersburg, in the county of Franklin 5 and State of Pennsylvania, have invented certain new and useful Improvements in Drop-Hammers, of which the following is a specification.

My invention relates to improvements in drop hammers and more particularly to improvements in the drop hammer shown in Letters Patent No. 1,037,735 issued to Henry E. Derbyshire on September 3, 1912.

My invention is illustrated in the accompanying drawings in which similar letters of reference indicate similar parts throughout the several views, and in which—

Figure 1, a front elevation of a board drop hammer embodying my improvements:

Fig. 2, a side elevation of the hammer shown in Fig. 1:

Fig. 3, a fragmentary front elevation, upon an enlarged scale, of the lower part of hammer shown in Fig. 1:

Fig. 4, a side elevation, upon an enlarged scale, of the lower part of the hammer shown in Fig. 2:

Fig. 5, a side elevation of pin 14 for locking front rod 9 in elevated position.

2 is the anvil and 3 the anvil cap of a board drop hammer, 4 the side frames of the hammer, 5 the ram, 6 the board carrying the ram, 7—8 the pulleys by means of which the elevating rollers which operate the board 35 which carries the ram are driven. All of these parts are well known and will not need detailed description.

9 is a bar or front rod the upper end of which is pivoted at 10 to the outer end of an 40 arm 11 which is connected with the eccentric means for carrying the front board elevating roll 25 in a well-known manner. This front rod, when the rolls 25—26 which elevate the board are out of contact therewith, rests upon a stop 12 carried in the frame 4 and carries a knock-off dog 13 which is engaged by the ram 5 in its fall to knock the lower end of the rod 9 off the stop 12 when the weight of this rod and its connected parts operate the eccentric means which cause the elevating rollers to grip and elevate the board 6 as described in the Derbyshire patent above referred to.

When the front rod 9 is knocked off its 55 seat or stop 12 it falls upon the top of a

plug 14, which is carried in a vertical hole 15 in the anvil 2. At its lower end the hole 15 is connected with a horizontal hole 16 through which leather or other washers 17 may be introduced to regulate the height of 60 the plug 14 and to form a cushion to take up the jar of the falling rod 9. The plug 14 may be made of different lengths, or may be adjusted by means of the washers 17, so as to regulate the fall of the rod 9. If the fall 65 of this rod is too great it will operate the elevating rolls to grip the board too tightly destroying it very quickly.

When the top dies are light and the work is die to die the elevating rolls 25—26 do not 70 have to grip the board as hard as when there is little rebound. When the work is nearly die to die considerable shock is transferred to all parts of the hammer, particularly the front rod, and consequently it will fall 75 harder and the elevating rolls will be locked tighter against the board than when there is only a slight shock. This means that the board will be pinched hardest when needed least unless some means be provided for 80 regulating the drop of the front rod.

Bottom stops for the front rod are not new but have heretofore been bolted or otherwise attached to the frame. Consequently all shock and jar from the falling front rod 85 was transferred to the frame. In the present invention all shock and jar is transferred through pin 14 directly to the anvil or base and this pin can be vertically adjusted and cushioned without the aid of bolts, nuts, or 90 pins, by the use of the washers 17.

All hammers require more friction between the board and elevating rolls on a short stroke than on a long one. Consequently the fall of the front rod should be 95 readily adjustable in order that proper and quick regulation may be given.

Near its lower end the rod 9 passes through a movable guide 18 which is held back against the frame 4 by a spring 19 100 which is carried in a pocket in the frame and at one end bears against one end of this pocket and at the other against a nut 20 carried by the outer end of the guide.

The knock-off dog 13 can be adjusted vertically on rod 9 to accommodate different heights of dies.

In the Derbyshire patent to which I have referred is shown a safety latch by means of which the front rod may be held in an 110

elevated position and the machine be prevented from working while repairs or adjustments are being made upon it.

In this invention I make use of the same safety latch but instead of this latch engaging the lower end of the front rod directly it engages and lifts the pin 14. To this end the pin 14 is notched or slotted out as at 21 to receive the short end of the bell 10 crank lever 22 which is pivoted at 23 and which carries the latch 24. If the longer arm of lever 22 be lowered its shorter arm will be raised, lifting with it the pin 14, until the top of the latter is on a level with 15 the top of stop 12; the latch 24 now hangs vertically, its lower end engaging a stop on the anvil 2, and the front rod 9 is prevented from falling, and the operating rolls from engaging the board and lifting the 20 ram, as shown in the aforesaid Derbyshire patent.

Having thus described my invention I claim as new and desire to secure by Letters Patent:—

- 25 1. The combination in a drop hammer of the hammer, lifting rolls, a bar for controlling the operative movements of said rolls, and a cushioned stop carried by the anvil for arresting the drop of said bar.
- 30 2. The combination in a drop hammer of the hammer, lifting rolls, a bar for closing said rolls, and an adjustable cushioned stop carried by the anvil for arresting the drop of said bar.
- 35 3. The combination in a drop hammer of the hammer, lifting rolls, a bar for controlling the closing of said rolls, an anvil furnished with a vertical hole and with a communicating horizontal hole, and a pin carried by said vertical hole for engaging the lower end of and for limiting the fall of said bar, and containing washers interposed between the lower end of said pin and the bottom of the vertical hole.
- 40 4. The combination in a drop hammer of the hammer, lifting rolls, a roll-controlling bar, an adjustable cushioned stop for arresting the fall of said controlling bar, a lever pivoted to the frame of the hammer, one of the arms of which is intended to engage and elevate said stop and a latch carried by said lever arm for holding said stop and
- 45 50

the roll-controlling bar in a raised position.

5. The combination in a drop hammer of the hammer, lifting rolls, a roll-controlling bar, a fixed stop upon which the roll-controlling bar rests, a spring actuated guide for holding said bar against the frame of the machine and upon said stop, a knock off dog operated by the falling ram for knocking said bar off its fixed stop, and a combined stop and cushion carried by the anvil for arresting the falling movement of said roll-controlling bar.

6. The combination in a drop hammer of the hammer, a ram connected therewith, lifting rolls, a roll-controlling bar, a fixed stop upon which the roll-controlling bar rests, a spring-actuated guide for holding said bar against the frame of the machine and upon said stop, a knock-off dog operated by the falling ram for knocking said bar off its fixed stop, a safety latch mechanism for holding the bar in raised position and a combined stop and cushion carried by the anvil for arresting the falling movement of said roll-controlling bar.

7. The combination in a drop hammer, of the hammer, lifting rolls, a bar for controlling the operative movements of said rolls, a stop holding the bar in raised position, a stop for limiting the fall of the bar and common means for adjusting the initial height of the second stop and cushioning it.

8. The combination in a drop hammer of the hammer, lifting rolls, a bar for closing said rolls, a vertically movable stop carried by the anvil of the hammer for arresting the drop of the bar and means for setting the stop at different initial heights.

9. The combination in a drop hammer of the hammer, lifting rolls, a roll-controlling bar, a stop for arresting the fall of said controlling bar, a lever pivoted to the frame of the hammer, one of the arms of which is intended to engage and elevate said stop and a latch carried by said lever arm for holding said stop and the roll-controlling bar in a raised position.

HOWARD TERHUNE.
